FOREIGN PATENT DOCUMENTS

WO 2007041295 4/2007

* cited by examiner

Primary Examiner — Marianne Pandozzi(74) *Attorney, Agent, or Firm* — Cynthia R. Parks; Parks IP Law LLC(57) **CLAIM**

We claim the ornamental design for a dispenser robot, as shown and described.

DESCRIPTION

FIG. 1 is a perspective view of an embodiment of a dispenser robot in accordance with our new design;

FIG. 2 is a right view thereof;

FIG. 3 is a left view thereof;

FIG. 4 is a front view thereof;

FIG. 5 is a back view thereof;

FIG. 6 is a top view thereof; and,

FIG. 7 is a bottom view thereof.

The uneven-length broken lines in the drawing represent the bounds of the claim and form no part of the claimed design. The even-length broken lines in the drawing depict portions of the dispenser robot that form no part of the claimed design.
